UNITED STATES PATENT OFFICE.

HEINRICH DÜNHÖLTER, OF BERLIN, GERMANY.

FARE-INDICATOR.

No. 868,849.

Specification of Letters Patent.

Patented Oct. 22, 1907.

Application filed April 26, 1907. Serial No. 370,393.

To all whom it may concern:

Be it known that I, HEINRICH DÜNHÖLTER, a subject of the King of Prussia, and a resident of 5 Neue Jacob Strasse, Berlin, Kingdom of Prussia, Germany, have 5 invented certain new and useful Improvements in Fare-Indicators, of which the following is an exact specification.

This invention relates to a fare-indicator for cabs and the like and has for its object a detent-device for a 10 signal, for instance in the form of a flag or the like convenient indicating means, from which it can be seen whether the cab is in use or is free. For the convenience of reference this signal will be hereinafter called "indicating-flag or flag," and as it is known the position of this indicating flag is usually thus selected that by having an upright and downward position the flag 15 indicates the cab in use and free respectively.

It is well known that when the flag and the fare indicator mechanism are thus in engagement with each 20 other that the flag cannot be put down prior to the throwing of the indicator into action and no lifting of the flag into the upright position can take place without having the indicator mechanism released, that is to say put out of action.

25 The indicating flag normally is mounted in the casing of the indicator and the indicating mechanism is thrown into or out of action either by means of a loose key or a handle fixedly connected with the mechanism. In known constructions the shaft to be operated 30 by the key is arranged apart from that shaft carrying the flag and special means as for instance suitably shaped disks, toothed wheels and detent pawls are provided for connecting both the aforementioned shafts and for rendering thereby the motion of the one 35 shaft in a certain manner dependent on the other shaft. These known constructions are rather cumbersome and the two openings for the shafts in the casing are very objectionable because rain or dirt can enter the interior of the casing thereby rendering the mechanism liable to injury. Furthermore the two shafts for the 40 indicating flag and the key or handle respectively require much space whereby the casing becomes large and heavy.

The present invention avoids the aforementioned 45 drawbacks and has for its object a considerable simplification of the fare-indicator. This purpose is attained by providing two telescoped shafts, which carry the indicating flag and the key or handle respectively. Besides simplifying the construction much space is 50 saved thereby, so that the casing of the indicator becomes smaller and furthermore one single hole is required for the passage of the two shafts through the casing.

In order to make my invention more clear, reference is made to the accompanying drawings, in which: 55 Figure 1 is a fragmentary side elevation of the indi-

cator, showing the improvement according to the present invention, Fig. 1^a is a fragmentary sectional front elevation of the indicator, Fig. 1^b is a fragmentary sectional plan elevation, Fig. 2 is a fragmentary vertical section on line A—B of the Fig. 1, Fig. 3 is a fragmentary vertical section on line C—D of the Fig. 1, Figs. 4 to 9 are details of the detent device for the indicating flag. Fig. 10 shows the detent device in the position permitting of the indicating flag to be laid 60 down, Fig. 11 illustrates the indicating flag laid down and the fare-indicator mechanism put into action. Fig. 12 illustrates the fare-indicator and the detent device respectively in the position permitting of the indicating flag to be lifted up in its vertical position. 70

Relating to the Figs. 1 to 9 *a* is the casing of the fare indicator.

b is a hollow shaft or sleeve into which is telescoped the shaft *e*. The sleeve *b* and the shaft *e* pass through an opening in the casing *a*.

75

c represents the indicating flag fixedly mounted on the sleeve *b* which is allowed to turn freely on the shaft *e*.

f is the handle fixedly connected with the shaft *e* and serving for throwing the indicating mechanism 80 into and out of action.

d is a ratchet wheel fixedly mounted on the sleeve *b* and *g* is a cam-disk or plate fixedly mounted on the shaft *e* and kept up against the wheel *d*.

f' is a helical spring for insuring the parts *g* and *d* in 85 their position and *f''* is a disk or washer serving as an abutment for the spring *f'*. *f'''* is a transverse rod or pin for preventing the washer *f''* from lateral movement.

i is a pivot carried by the casing *a* and *h'* and *h''* are 90 two ratchet pawls pivoted to the shaft *i* and being of a particular shape. The free end of the ratchet pawl *h'* is provided with two projections or peaks *k'* *k''*, leaving an interstice *k'''* between them, (see Fig. 6, which is a plan elevation of the ratchet pawl *h'* according to 95 Fig. 5). Fig. 8 illustrates the ratchet pawl *h'* in a front elevation.

g' is a curved ledge or tongue (see Fig. 9) which is attached to the cam plate *g* being provided with a circumferential depression *g''*. As to be seen from Fig. 100 1^a the tooth *k'* rides on the ratchet wheel *d* and the tooth *k''* bears on the tongue *g'*, and the recess *k'''* takes over the cam-plate *g*. The tooth *h''* of the ratchet pawl *h'* is of such a width, that it is adapted to bear temporarily against the ratchet wheel *d* and the circumference of the cam-plate *e*, as to be seen from Fig. 1^a and Fig. 7, in which latter figure the pawl is illustrated removed from the ratchet wheel. *g'* and *g''* are two stops or pins nearly diametrically and fixed to the cam plate *g* (see Figs. 1 and 4).

105

r is a detent lever provided with a right-angled extremity *r'* (see Fig. 1^b) and pivoted at *r'* to the casing *a*.

110

r^2 is a projection on the detent lever r , riding therewith on the cam disk m loosely mounted on the shaft m^2 and provided with the circumferential depression m' .

o is a toothed wheel which meshes with a ratchet wheel d and is fixedly connected with a cam-disk m . The shaft m^2 is carried by the casing a .

It will be observed that the hook r^3 is adapted to interfere either with the stop g^2 or the stop g' .

The operation of the foregoing described mechanism 10 is as follows:—As it will be observed from Fig. 1 the indicating flag c cannot be put down because the tooth k^3 of the spring-pressed pawl h' engages with the ratchet wheel d .

This engagement is permitted as the depression g^3 is opposite to the tooth k^3 of the ratchet pawl h' . 15 For the purpose of releasing the ratchet wheel from the pawl h' , the handle f and the cam plate g respectively are rotated in the direction of the arrow I (see Fig. 1). Due to this rotation the tooth k^3 is engaged by the ascending part g^5 of the circumference of the cam plate g .

20 whereby the pawl h' and the ratchet wheel d are disengaged. At the same time the spring-pressed pawl h^2 is riding on the curved tongue g^4 thus preventing the tooth k^2 from engaging with the ratchet wheel d . The cam plate g and the handle f respectively are rotated until the stop g' pushes against the hook k^3 . Then 25 the peak k^2 has fallen down from the curved tongue g^4 and the peak or tooth k' engages with the ratchet wheel d . This position is illustrated in the Fig. 10, and now the indicating flag c can be put down. By the rotation of the flag arm the cam disk m and the toothed wheel o engaging with the ratchet wheel d are also turned round, till the projection r^2 slides into the depression m' .

The detent lever r is thereby lowered and the hook r^3 is moved downwardly and thereby removed 30 from the path of the stop g' (see Fig. 11). In the position occupied by the various parts of the detent-device according to Fig. 11 the indicating flag cannot be placed vertically owing to the engagement of the spring depressed pawl h^2 with the ratchet-wheel d . For disengaging these parts to enable the indicating flag to be placed vertically the handle f is further rotated in the 35 direction of the arrow I, whereby the peak k^2 engages with the curved tongue g^4 and disengages thereby the tooth k' from the ratchet wheel d .

This disengagement has taken place when the stop g^2 interferes with or pushes against the hook k^3 (see Fig. 12). Now the indicating flag can be turned in the direction of the arrow II (see Fig. 12) in its upright position. At the same time the cam plate m and the toothed wheel o respectively are rotated and the hook r^3 thereby is disengaged from the stop g^2 . Now the detent-device occupies its initial position, as illustrated in Fig. 1.

It may be observed that the movement of the cam plate g must be controlled by a detent device or in any 50 other convenient manner, as it is well-known, that the cam plate is allowed to be rotated in only one direction.

This arrangement is of itself well known and is therefore not further illustrated.

Having thus fully described the nature of my invention, what I desire to secure by Letters Patent of the 60 United States is:—

1. In a fare-indicator, the combination, with a casing provided with a hole, of two telescoped shafts, passing through said hole in the casing, a signal carried by the one shaft and means for rendering the movement of the 65 one shaft dependent on the movement of the second shaft, and means for operating the second shaft.

2. In a fare-indicator, the combination with a casing, of hollow shaft or sleeve passing through an opening in the casing, a solid shaft telescopically arranged in the said sleeve, and adapted to be rotated, an indicating flag fixedly mounted on the sleeve and adapted to be turned therewith, a handle fixedly connected with the solid shaft, a ratchet wheel fixedly mounted on the sleeve, a cam-plate keyed on the solid shaft, a detent device for controlling 70 the movement of the ratchet wheel and the indicating flag respectively, and a detent device for controlling the movement of the cam-plate.

3. In the herein-described combination with a casing and two telescoped shafts (b and e), a detent device for 80 controlling the movement of the shaft (b), consisting of a ratchet wheel fixedly mounted on the telescopic shaft (b), a cam plate (g) keyed on the shaft (e) and having a depression (g³), a curved tongue (g⁴) attached to the cam plate, a spring-pressed ratchet pawl (h') (h²) having an 85 enlarged detent tooth riding therewith, on the ratchet wheel and the cam-plate, and a spring-pressed ratchet pawl, both pawls being pivoted to the casing and the latter having two peaks or teeth riding on the cam plate and the ratchet wheel respectively. 90

4. In the herein-described combination with a casing and two telescoped shafts (b and e), a detent device for controlling the movement of the shaft (c), consisting of a cam plate (g) having a depression (g³) and fixedly mounted on the shaft (c), two stops (g', g²) attached to 95 the cam plate, a curved tongue (g⁴) attached to the cam plate, a detent lever (r) pivoted to the casing and cooperating with its free end with the said stops, a cam disk and a toothed wheel connected with each other and turnably carried by the casing, the cam-disk supporting the 100 said detent lever, and a handle fixedly connected with the shaft (e).

5. In a fare indicator, the combination with a casing, of two telescoped shafts (b and e), an indicating flag (c) and a handle being secured to the shafts (b and e) respectively, a ratchet wheel and a cam plate having a depression and two stops, fixedly carried by the shafts (b and e) respectively, a curved tongue attached to the cam plate, a ratchet pawl pivoted to the casing and riding with its enlarged detent tooth on the cam plate and the ratchet wheel, a ratchet pawl pivoted to the casing and riding with its two peaks or detent teeth on the ratchet wheel and the curved tongue respectively, a detent lever pivoted to the casing and cooperating with its free end with the said stops, a cam disk and a toothed wheel fixed to each 110 other and turnably carried by the casing, the toothed wheel engaging with the said ratchet wheel, the cam disk supporting operatively the detent lever. 115

In witness whereof I have hereunto set my hand in the presence of two witnesses.

HEINRICH DÜNHÖLTER.
